CLAIM

I claim the ornamental design for vehicle cab, as shown and described.

DESCRIPTION

FIG. 1 is a left front perspective view of a vehicle cab.

FIG. 2 is a right front perspective view of a vehicle cab.

FIG. 3 is a front view of a vehicle cab depicted in FIG. 1.

FIG. 4 is a rear view of a vehicle cab depicted in FIG. 1.

FIG. 5 is a right-side view of a vehicle cab depicted in FIG. 1.

FIG. 6 is a left-side view of a vehicle cab depicted in FIG. 1; and,

FIG. 7 is a top view of a vehicle cab depicted in FIG. 1. Broken lines in the drawings show portions of the vehicle cab that form no part of the claimed design.
